RUBBER SAFETY SOCKET

Lloyd J. McPartlin and Henry V. Harding,
Detroit, Mich.

Application April 16, 1930, Serial No. 444,709

6 Claims. (Cl. 173—358)

This invention relates to a rubber safety socket especially adapted for temporary use in repeatedly diverse locations, as for example, in the illumination of a partially finished building, and has for its object an improved organization of parts adapted to permit the convenient and safe handling, installation, and removal of a string or series of electric light bulbs by means of which it is desired to temporarily illuminate a selected area, and wherein the incomplete state of the building's installation, such as its wiring system, precludes reliance thereon as a means of securing the desired illumination. Both the safety of the device as regards handling, and its durability under more or less rough usage, as well as its easy adaptation to the support of such devices or series in multiple or parallel lines, from a single wire or other support, are purposes to which our improved construction readily lends itself.

20 In the drawing:

Figure 1 is an elevational view of a single rubber armored socket, with portions of a current-carrying cable extending from either side thereof.

Figure 2 is a largely sectional elevational view 25 of the construction shown in Figure 1.

Figure 3 is a sectional elevational view taken along the line 3—3 of Figure 2.

Figure 4 is a small scale elevational view of a string or series of lighting units, the several bulbs 30 of which are designed to receive their illuminating current from a single easily detached terminal.

A represents a cut-in plug, whose terminal prongs are adapted to be inserted in the corresponding recesses of any suitable source of electrical energy, and B represents a current-carrying cable leading therefrom, the range of selection as to its length being indicated by the broken portion B'. Between two adjacent portions or sections of this cable there is a cut-away portion as regards the insulating cover D, the removal of which leaves the wires E and F exposed for connection to the terminal wires G and H leading respectively from connection with the shell of the bulb socket K and from the disc J, which forms the top end of the bulb socket K; the contact leaf piece L of the disc J is adapted to be engaged in the usual manner by the inner end of the threaded base or plug. Soldering or other equivalent means for uniting the terminal cords G and H with the current-carrying wires E and F are shown at M.

With the parts as thus far described adequately assembled in an electrical sense, there is positioned enclosingly about them, including the sides 55 of the threaded socket K, a mass of rubber or

equivalent insulating material which is also made to surround the ends of the cable sheathing which have not been removed, as shown at N. Before the positioning of this rubber mass about these parts and before the vulcanization thereof, however, a generally U-shaped cord or wire P is also positioned in inverted position with relation to the parts thus far described with its knotted ends, as Q, extending well down into the mass or body of the surrounding rubber or other insulating material, and when the vulcanization of the latter has been completed, the legs of this U-shaped piece form the backbone or reinforcement of an upstanding rib, as R, which may be tapered off as shown elevationally in Figure 1, 60 to graceful union with and about the ends of the insulated cable elements B and C, and through the top portion of this upstanding rib, a reinforcing metal eyelet, as S, is preferably placed in a position within, that is to say, below the middle 65 portion of the inverted U-shaped piece M; thus when the vulcanization of the protective rubber mass has been completed, this eyelet S, integrated with the rubber, constituting the rib R, furnishes a means through which a supporting 70 cord or wire may be strung or through which the end of a wall hook or the like may be passed to graceful union with and about the ends of the insulated cable elements B and C, and through the top portion of this upstanding rib, a reinforcing metal eyelet, as S, is preferably placed in a position within, that is to say, below the middle 75 portion of the inverted U-shaped piece M; thus when the vulcanization of the protective rubber mass has been completed, this eyelet S, integrated with the rubber, constituting the rib R, furnishes a means through which a supporting 80 cord or wire may be strung or through which the end of a wall hook or the like may be passed to effect the support of a series of these elements, such as Figure 4 illustrates, in desired relation to the space to be illuminated. Whether the 85 support be afforded by a wire, hooks, or any other selected means, the insulation of the current-carrying parts is at all times so complete that the individual sockets can be handled with entire 90 safety, and yet the weight of the several sockets and their feeding wires or cables is supported by a part of the rubber structure as a whole, which is reinforced externally of the eyelet S by the 95 passage thereover of the inverted portion of the U-shaped member M.

It will thus be seen that whether a single string of lights be supported, as illustrated elevationally in Figure 4, or whether a suitably spaced group of such lights arranged in parallel or other relation, and each of the general character shown 100 in Figure 4, be employed, the illumination of the space or area desired may be executed, as for example for the installation of a tile or wooden floor over the I-beam and cement structure of a building skeleton, without reliance upon the permanent wiring system of the building, which may not have as yet been installed. When the requirement for illumination of the space in question is at an end, the parts, whether hook or wire-supported, can be easily taken down without 110

injury or danger, for removal to an installation in another space, the terminal plug A being then placed in contact with what terminal may then and there be available.

5 The most frequently resorted-to use of the apparatus herein disclosed is, of course, illumination, and for the sake of clarity we have so spoken thereof in the foregoing description; it should be understood, however, that the socket terminals mentioned are equally adaptable to the taking off of current at selected points for other power users, such as the actuation of small electrically driven drills, electric soldering irons or the like.

10 What we claim is:

- 15 1. In a safety socket, in combination with a shell portion for the reception of a plug base, a current-carrying cable from a selected portion of which the insulating covering has been removed for the electrical connection with the wires thereof of the terminal connections of said shell portion, a mass of yieldable insulating material positioned about the otherwise exposed portions of the elements thus far recited, and means anchoringly embedded in said mass and extending 25 above an aperture in the upper portion thereof whereby the strain incident to the suspended support of the recited parts is distributed through relatively remote portions of said insulating mass.
- 20 2. In combination, a lamp socket, yieldable insulating means surrounding said socket and including a bore, and inextensible means, substantially co-planar with the longitudinal axis of said socket, at least partially encircling said bore and imbedded in the insulating means.
- 25 3. In combination, a lamp socket, yieldable insulating means surrounding said socket and including a bore, and inextensible means at least

30 partially encircling said bore and imbedded in said insulating means at a distance from said bore for distributing through said insulating means stresses applied thereto in a direction parallel to the longitudinal axis of said socket.

35 4. In combination, a lamp socket, current carrying connections to the socket, yieldable insulating means surrounding said socket and said connections and including a bore, and inextensible means, substantially co-planar with the longitudinal axis of said socket, at least partially encircling said bore and imbedded in the insulating means for a distance from said bore for distributing through said insulating means stresses applied thereto at said bore.

40 5. In combination, a lamp socket, yieldable insulating means surrounding said socket and including a bore, and inextensible means, substantially co-planar with the longitudinal axis of said socket, at least partially encircling said bore at a distance therefrom, and imbedded in the insulating means for a distance extending from said bore, for distributing through said insulating means stresses applied thereto in a direction parallel to the longitudinal axis of said socket.

45 6. In combination, a plug-receiving socket, yieldable insulating means associated with said socket and having an aperture therein, the axis of said aperture lying at an angle to the longitudinal axis of said socket, and anchoring means embedded in said insulating means adjacent said socket and extending around said aperture, whereby stresses applied to said insulating means at said aperture are distributed throughout said insulating means.
